UNITED STATES PATENT OFFICE.

WALTER JAMES, OF CAIRO, IOWA.

AIR-COOLING SYSTEM FOR INTERNAL-COMBUSTION ENGINES.

1,315,843.

Specification of Letters Patent. Patented Sept. 9, 1919.

Application filed May 2, 1917. Serial No. 166,063.

To all whom it may concern:

Be it known that I, WALTER JAMES, a citizen of the United States, residing at Cairo, in the county of Louisa and State of Iowa, have invented certain useful Improvements in Air-Cooling Systems for Internal-Combustion Engines, of which the following is a specification, reference being had therein to the accompanying drawing.

10 The present invention has reference generally to improvements in that class of inventions known as internal combustion engines and more particularly relates to an improved air cooling system for internal combustion engines preferably of the type employed in motor vehicles.

As the primary aim and object, the present invention contemplates the provision of novel fan means operably connected to the 20 drive shaft of an explosive engine providing a suction for drawing cool air into the fan casing and for forcing the cool air through the jackets of the engine cylinders whereby to cool the engines, thus preventing over-heating of the engine during actuation.

More particularly, the present invention contemplates the provision of novel means for rigidly connecting the fan in rigid yet removable relation with respect to the shaft 30 and for bracing the blades of the fan.

As a further improvement the invention consists in the provision of novel means for journaling the shaft in the fan casing so as to insure of an effective rotation of the 35 shaft.

Still further, the invention contemplates the provision of improved means operably mounted on the casing for tightening the belt which is trained about a wheel on the 40 shaft.

More specific objects of the present invention reside in the provision of the means for mounting the belt engaging wheel on the shaft; to provide novel means for conducting air from the fan casing to the jackets of the cylinders; and to provide improved means for removably connecting the fan casing to the hood support.

Among the other aims and objects of the 50 present invention may be recited the provision of a device of the character mentioned with a view to compactness, and in which

the number of parts are few, the construction simple, the cost of production low, and the efficiency high.

Other improvements and novel details in the construction and arrangement of the various parts of the apparatus will be brought out more in detail in the description to follow, which for a clear understanding of the invention, should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the spirit of the invention or the principle 65 of operation of the various parts.

The preferred embodiment of the present invention is clearly illustrated in the accompanying drawings, in which:

Figure 1 is a side elevation of the invention.

Fig. 2 is a vertical longitudinal section thereof.

Fig. 3 is a horizontal section taken on line 3—3 of Fig. 2.

Fig. 4 is a vertical transverse section taken on line 4—4 of Fig. 2, and

Fig. 5 is a detail of the belt tightening means.

Similar characters of reference are employed in all of the above described views, to indicate corresponding parts.

Referring now, more particularly, to the accompanying drawings there is provided a main upright support 1 which is connected 90 to the front end of the frame of the vehicle and serves as the front of the hood thereof, being provided with a central opening 2 in which is mounted a frusto-conical washer 3 the forward end of which passes through 95 the opening and projects beyond the front face of the support, terminating in an annular groove 4 in which is mounted a ring 5 carrying a piece of reticulated material 6 and through which cool air is adapted to 100 be drawn.

With a view toward providing the improved fan means a cylindrical casing 6' is removably connected to the inner surface of

the support and about the opening 3 preferably by means of elongated bolts 7 the free ends of which are engaged by nuts 8 which serve to clamp the casing against the support. The casing is provided with a central opening 9 in which is mounted a cup 10 for receiving ball bearings 11 and through which a threaded shaft 12 is journaled. A frusto-conical washer 13 is threaded on the shaft and coöperates with the cup in retaining the ball bearings in position. A circular plate 14 is provided with a central opening 15 which is held in registration with the opening 9 by means of suitable fastening devices 16 which rigidly connect the plate to the outer face of the casing. Another cup 17 is rigidly mounted in the opening in the plate and abuts the cup 10. Ball bearings 18 are receivable in the cup 17 and held in place by a frusto-conical washer 19 which is adjustably engaged on the shaft 12 and coöperates with the washer 13 in preventing longitudinal movement of the shaft and at the same time facilitates the rotation of the shaft. The fan proper consists of a disk 20 having a central opening therein for receiving the shaft. Washers 21 are arranged about the shaft and abut the disk to facilitate the rigid mounting of the disk on the shaft. A plurality of blades 22 are now provided the inner edges of which are provided with opposed supporting flanges 23 and with securing tongues 24 which pass through the disk so as to clamp the blades 35 in a plane at right angles to the disk and radially thereof. The edges of the blades adjacent the center of the disk are provided with recesses 25 for accommodating the washers 22 and are further provided with extensions 26 engageable by the radially arranged notches 27 in the periphery of the annular flange 28 formed on the interiorly threaded adjustable sleeve 29. This sleeve is adjustably mounted on the outer end of 45 the shaft and serves to clamp the washers and the disks against the adjacent face of the washer 13, the arrangement of the notches and the extensions serving to brace the blades while a nut 30 serves to removably hold the sleeve in a rigid position on the shaft. It will likewise be noted that the beveled edges of the blades are positioned slightly within the frusto-conical shaft 3 so that when the shaft is rotated the fan will 55 be rotated so as to draw air through the reticulated piece 6 into the the casing 6'.

With a view toward providing suitable means for insuring of the passage of cool air into the jackets of the engine cylinders 60 31 a pipe 32 is provided and has one end connected to the adjacent cylinder 31 and arranged in communication with the jacket thereof and the offset end connected to the offset portion 33 on the casing 6' which

offset portion is arranged in communication 65 with the interior of the casing by means of registering openings 34 so that the air drawn into the casing 6' will be forced through these openings 34 from the pipe and thence through the cylinder jackets so as 70 to cool the engine, and prevent overheating thereof.

In order to rotate the shaft 12, a pulley wheel 35 is mounted thereon rearwardly of the casing 6' while nuts or suitable adjusting elements 36 coöperate with washers 37 and hold the washers in frictional engagement with the respective ends of the pulley wheel so as to rigidly connect the latter to the shaft. A belt 38 operates about the pulley wheel 35 and also about another pulley wheel 39 carried by the rotatably mounted stub shaft 40 in the forward portion of the engine. A relatively large gear 41 is also carried by the projecting end of the main drive shaft 43 of the engine of the vehicle with which the device is associated. By this arrangement it will be appreciated that because of the arrangement of the gears 42 and 41 and the belt connection between 90 the shafts 40 and 12 that the speed of the shaft 12 will be greater than the speed of the drive shaft to insure of an effective operation of the fan means.

In order to adjust the relation of the belt 95 with respect to the pulley wheel 35 and at all times maintain the belt in relatively tight relation with respect to the pulley wheel improved belt tightening means have been provided in the present instance consisting 100 of a supporting frame formed desirably from a single piece of material such as relatively thick wire which is bent upon itself and has portions 44 adjacent the bend arranged in spaced parallel relation with each other to provide a slot 45. A U-shaped portion 46 continues from and is offset from one of the portions 44 while the outer end of this section of the wire terminates in a loop 47 which is resiliently connected to the plate 14 by means of the coil spring 48. The other section or portion of the wire is extended at right angles and looped about the U-shaped portion as indicated by the numeral 50, the portion 51 continuing therefrom serving in the capacity of a stub shaft upon which is rotatably mounted a spool 52 prevented from accidental displacement by a nut 53 on the portion 51. The spool is adjusted to engage one lay of the belt 39 115 in the manner indicated so as to insure of an effective frictional engagement between the belt and the respective pulley wheels while the frame itself is adjustably mounted on the casing 6' by means of a suitable fastening device such as a screw 54. It will be appreciated that by loosening the screw the frame may be slid through the medium of a 120 125

slot 45 and subsequently tightened to maintain the frame in a proper position. Suitable means have been provided for lubricating the bearings in the present instance consisting of a manually controlled lubricating device 55 mounted in the upper portion of the plate 12 as indicated.

The mode of operation of the present invention may be reviewed as follows:

10 Assuming that the parts have been assembled in the manner described, upon actuation of the drive shaft 43 rotary motion will be imparted to the stub shaft 40 owing to the meshing gears 42 and 41 carried by 15 the respective shafts so that the shaft 40 will rotate faster than the shaft 43. Owing to the belt 38 trained about the pulley wheel 39 on the shaft 40 and about the pulley wheel 35 on the shaft 12 the latter shaft will 20 be rotated at a corresponding rate of speed to consequently rotate the fan which draws cool air through the reticulated piece 6 into the casing 6' and forces the cool air through the registering or alining openings 34 respectively formed in the casing 6' and the 25 offset portion 33; and through the pipe 32 into the jacket of the engine cylinder 31. Of course this operation will be continuous during the actuation of the engine so as to 30 prevent the overheating of the same.

As many changes could be made in the above construction and many apparently widely different embodiments of this invention could be made without departing from 35 the scope thereof, and it is intended that all matter contained in the above description or shown in the accompanying drawings shall be interpreted as illustrative and not in a limited sense. It is also to be understood 40 that the language used in the following claims is intended to cover all the generic and specific features of the invention herein described and all statements of the scope of the invention, which, as a matter 45 of language might be said to fall therebetween.

Having thus fully described this invention, what is claimed as new and desired to be secured by Letters Patent, is:—

50 1. An air cooling system for internal combustion engines of motor vehicles including a frusto-conical shell mounted in the front end of the hood of the vehicle and projecting therefrom, a reticulated covering for the 55 shell, a casing removably mounted on the inner face of the front end of the hood and in the rear of the shell and provided with a small central opening, a plate secured to the rear face of the casing and provided with 60 a small central opening, ballbearing receiving cups disposed in the small openings and alining with each other, ballbearings in the cups, a shaft having its threaded portion journaled through the cups, washers car-

ried by the threaded portion of the shaft for coöperating with the cups, a fan mounted on the inner end of the shaft and disposed in the casing for drawing cold air through the reticulated covering, means for operably connecting the shaft with the main shaft of the engine, and a pipe leading from the casing and connected to the jacketed cylinder of the engine and through which the air is forced by the fan.

2. An air cooling system for internal 75 combustion engines of motor vehicles including a frusto-conical shell mounted in the front end of the hood of the vehicle and projecting exteriorly therefrom, a screen covering the shell, a casing removably 80 mounted on the inner surface of the front end of the hood and in the rear of the shell and provided with a central opening, a shaft having its threaded portion journaled in the opening in the casing, a fan mounted on 85 the shaft and arranged within the casing for drawing air through the screen into the casing, said fan embodying a disk rigidly connected to the shaft, a plurality of blades, securing flanges projecting from the blades 90 and anchored to the disk so as to position the blades at right angles thereto and radially thereof, extensions projecting from the inner edges of the blades, an adjustable element mounted on the free portion of the 95 shaft and engageable with the extensions to increase the rigidity of the blades, means for operably connecting the threaded shaft with the main shaft of the engine, and a pipe leading from the casing and connected 100 to the jacketed cylinder of the engine.

3. An air cooling system for internal combustion engines of motor vehicles including a frusto-conical shell mounted in the front end of the hood of the vehicle 105 and projecting exteriorly therefrom, a screen covering the shell, a casing clamped to the rear face of the front end of the hood rearwardly of the shell and provided with a central opening, a plate secured to the rear 110 face of the casing and also provided with a central opening, bearing cups mounted in the opening in the casing and the plate, ballbearings receivable in the cups, a shaft having one portion threaded and rotatably 115 mounted in the cups, conical washers adjustable on the threaded portion of the shaft for coöperating with the bearings in the cup for preventing longitudinal displacement of the shaft, a fan connected to the 120 shaft for drawing air through the screen into the casing, said fan consisting of a disk disposed about the shaft and within the casing, a plurality of blades, securing flanges projecting from the blades and anchored to the disk, extensions projecting 125 from the edges of the blades near the center of the disk, a sleeve adjustably mount-

ed on the threaded portion of the shaft, an annular flange projecting from the sleeve and formed with notches for engaging the extensions to increase the rigidity of the 5 blades, a pulley wheel on the outer end of the shaft, a supplemental rotatable shaft operatively connected to the main shaft of

the engine, a belt trained about the pulley wheels, and a pipe leading from the casing and connected to the jacketed cylinders of 10 the engine and through which air is forced.

In testimony whereof I affix my signature.

WALTER JAMES.
